UNITED STATES PATENT OFFICE.

HENRY H. MARKLEY AND ALPHONSE MATHIEU, OF SAN FRANCISCO, CAL.

DESIGN FOR A WATCH-CHAIN.

Specification forming part of Design No. 6,884, dated September 16, 1873; application filed June 13, 1873.
[Term of Patent 7 years.]

To all whom it may concern:

Be it known that we, HENRY H. MARKLEY and ALPHONSE MATHIEU, of San Francisco, California, have invented a Design for a Watch-Chain, of which the following is a specification:

The nature of our design is fully represented in the accompanying drawings, to which reference is made.

A, Figure 1, represents a single link of the chain. This link consists of an open frame, having a triangular section, as shown in Fig. 2. An opening, *c*, is left on each side of the cross-bar *d* to receive any setting that may be selected. Along each angle of the link we make a fancy molding, *o*.

Having thus described our invention, what we claim, and desire to secure by Letters Patent, is—

The design for a watch-chain, as described and shown, formed essentially of a triangular open-bar link with a fancy molding.

In witness whereof we hereunto set our hands and seals.

HENRY HARTER MARKLEY. [L.S.]
ALPHONSE MATHIEU. [L.S.]
